UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW YORK.

LINE-SEPARATING MECHANISM FOR LINE-CASTING MACHINES.

1,172,309.

Specification of Letters Patent.

Patented Feb. 22, 1916.

Application filed October 23, 1914. Serial No. 868,175.

To all whom it may concern:

Be it known that I, DAVID PETRI-PALMEDO, a citizen of the United States, residing at Bridgeport in the county of Fairfield and 5 State of Connecticut, have invented a certain new and useful Improvement in Line-Separating Mechanism for Line-Casting Machines, of which the following is a full, clear, and exact description.

10 This invention is designed to be a part of a circulating matrix, type-bar casting machine, and particularly a machine of this sort which utilizes matrices having laterally extended ears near their tops, and space 15 bands having supporting ears which are in a plane below said upper ears of the matrices when matrices and space bands are assembled to form a line.

20 The object of the invention is to separate the matrices and space bands in such a line, and to deliver the space bands to their magazine, and the matrices to the second elevator by which they will be carried and delivered to the matrix distributing mechanism.

25 The invention consists in the construction and combinations of parts shown in the appended drawing, and hereinafter described and definitely set forth in the appended claims.

30 In the drawing, Figure 1 is a front elevation of those parts of a circulating matrix line casting machine which has to do with the present invention. Fig. 2 is a transverse 35 vertical section in the plane of line 2-2, on Fig. 1. Fig. 3 is a sectional plan in the plane of line 3-3 on Fig. 1. Fig. 4 is a front elevation of the mechanism which is shown in Fig. 3 with some of the parts 40 broken away. Fig. 5 is a vertical sectional view of certain parts in the plane of line 5-5 on Fig. 4. Fig. 6 is a side elevation of the first elevator. Fig. 7 is a side view of one of the space bands adapted to be used 45 in the machine.

46 Referring to the parts by reference characters, 10 represents the so-called first elevator. This is a vertically movable device constructed so that it may support an assembled line of matrices and space bands 50 while a type bar is being cast from it. This elevator may be supported and guided by any suitable means; for example, it may have vertical guide ribs 10^a which slide in

guideways behind gibs 10^b. This elevator 55 includes what may be termed two horizontal supporting rails 10^a, 10^b, suitably separated, and having in their opposed faces the grooves 10^b, 10^a, for the reception of the upper ears *m* of the matrices *M*; and other 60 opposed grooves 10^a, 10^b, for the reception of the lower ears *m*¹ of the matrices and also of the ears *s* of the space bands *S*, which space bands, as shown in Fig. 7, have only the two ears which are adapted to enter 65 these lower grooves.

12, 12 represent the transfer rails which are fixed to a part of the framework of the machine; and these rails communicate directly with the space band magazine 13. 70 When the space bands suspended from their ears rest upon these rails, they may be pushed along the rails directly into the so-called space band magazine. These rails are located one behind the other, and such a 75 distance apart that the space bands may pass between them while the ears *m*¹ and *s* project over and may engage the top edge of said rails.

The second elevator 14 is also vertically 80 movable, and may be moved up and down on two guide rods 14^a by suitable mechanism. This elevator includes two downwardly extended matrix suspending rails 14^a suitably spaced, and having in their opposed faces, 85 and extending from one end to the other thereof, the horizontal grooves 14^b which the upper ears of the matrices may enter. After a type bar has been cast from an assembled line of matrices, the first elevator 90 goes up, carrying a line of matrices and space bands suspended by their ears which project into the grooves 10^b, 10^a thereof. This first elevator goes up to and stops in such position that the lower walls of the 95 lower grooves 10^a are alined with the upper edges of the transfer rails 12. When the first elevator reaches this position, the second elevator is down, and its rails 14^a are over the transfer rails, and in such position 100 relative to the first elevator that the grooves 10^b and 14^b are alined, and the adjacent ends of the rails 10^a and 14^a are in substantial contact.

105 A line transfer slide 15, and a space-band transfer slide 16 are mounted in guideways in the fixed framework of the machine, so that they are compelled, when they move,

to move horizontally to right or left. The line transfer slide has an offset upwardly extended pusher arm 15^a of such size and shape that it may extend up between the 5 two rails 10^a of the first elevator and engage the left end matrix of the line therein.

The space band transfer slide 16 has a pusher arm 16^a which is pivoted to it on a vertical pivot, and this arm is under the influence of a spring 16^b which acts to move said pusher arm to the position shown in Fig. 3, where it extends forward so that it may engage the left space band of those which are supported on the transfer rails.

15 This pusher arm projects through a slot 12^a in one of the transfer rails 12. When the slide 16 is moving toward the left end of its path, this pivoted pusher arm will engage the left end of the slot 12^a and will thereby be swung backward to the position shown by dotted lines in Fig. 3, in which position it is behind the path in which the matrix line travels in moving into the second elevator and along the transfer rails.

20 25 When the first elevator has reached the top of its path of travel, the second elevator is at the bottom of its path of travel, and both transfer slides are at the left ends of their paths. The line transfer slide 15 is the first of the described parts to begin to move; and it moves to the right, pushing the line of matrices and space bands ahead of it,—the upper ears of the matrices entering the grooves 14^b of the second elevator, and the 30 ears of the space bands (and the lower ears of the matrices), going over the transfer rails 12.

35 40 When the line transfer slide reaches the right end of its path, it stays there until the first elevator has gone down. The second elevator, immediately after the matrices have passed into its embrace, begins its upward movement, carrying up the matrices, and leaving the space bands behind on the transfer rails. As the second elevator begins its 45 upward movement, the space band transfer slide 16 begins its movement to the right. The pivoted pusher arm 16^a will be freed from the restraining action of the end of the slot 12^a, and will swing forward into such position

50 55 that it may engage the left one of the space bands suspended on the transfer rails. As this slide continues its movement to the right, this pusher arm will push the space bands along the transfer rails, and into the space band magazine 13. While the particular form of this magazine is no part of the present invention, it might be said that this magazine, as shown, is substantially like that which is fully described in my co-pending application Serial No. 842,859, filed June 4, 1914. It consists of two parallel rails 13^a having inclined grooves 13^b in their opposed faces,—the upper entrance end to 60

65 said grooves being alined with the said transfer rails. Suitable escapement mecha-

nism is to be provided for holding the space bands in this magazine, and for releasing them one by one as required.

When the second elevator has reached the top of its path it stays there long enough for 70 the matrices to be pushed to the right therefrom onto the distributing rails 18, which may be considered a part of the matrix distributing mechanism. After this, the second elevator descends, and the space band transfer slide concurrently moves to the left end of its path, until these parts reach the first described positions in which they will be found when the first elevator again moves up, bringing another assembled line of 75 matrices and space bands.

What mechanism is employed for moving the first elevator 10 up and down is of no importance to the present invention. It might even be moved by hand. It is, however, desirable that the arrival of the first elevator at the top of its path shall be immediately followed by the described sequential movement of the other parts; and, as will appear later, means are provided for securing 80 this result.

The particular mechanism shown for causing the second elevator 14 to move up and down is not essential to the present invention, although it is desirable that the mechanism employed for this purpose shall begin to perform its functions immediately after the matrices of a line have been moved into the embrace of the second elevator.

In the construction shown, the line transfer slide 15 is fixed to one leg of a sprocket chain 32, which runs over a driven sprocket wheel 31, and an idler sprocket wheel 33. The sprocket wheel 31 is fixed to a shaft 30 which is turned in one direction or the other through a train of gears, of which one gear 30^a is fixed to the shaft 30. The first gear 29 of the train is engaged by the teeth of a rocking gear segment 27 which is loosely pivoted on a fixed stud 28. When this gear segment 100 is swung down, it will, through said train of gearing, cause the upper leg of the sprocket chain to move to the right, and thereby cause 105 the line transfer slide 15 to move with it in the same direction, thereby pushing the line from the first elevator and causing the matrices to enter the second elevator, and the space bands to slide onto the transfer rails. When this gear segment swings up, 110 these movements are reversed. The gear 115 segment is caused to rock back and forth in the desired manner after the first elevator has reached the top of its path by mechanism, which, as before stated, is very like the mechanism shown and described in Letters Patent No. 1,080,569. This includes a normally idle cam shaft 23, on which a sleeve 21 is rotatably mounted. This sleeve 120 is to be in constant rotation, which result may be secured by a constantly driven worm 125

24, and a worm wheel 21^b which is engaged thereby and fixed to the sleeve 21. Adjacent to this sleeve 21, for the purpose of connecting it and the cam shaft when this is required and for automatically disconnecting them when the cam shaft has made one complete revolution, is a clutch sleeve 25 and associated devices substantially like the clutching mechanism shown and described in said prior patent. This clutch sleeve has a sliding tongue and groove connection with the shaft. It carries at one end jaws 25^a for engagement with clutch jaws 21^a on the sleeve 21. There is a spring 25^b for moving the clutch sleeve in the clutching direction. This sleeve has in its surface a cam groove 25^c adapted to receive a pin 26 which, by engaging the cam groove as the sleeve is rotated, will cause the sleeve to move endwise in the unclutching direction, and thereby carry its jaws out of engagement with the jaws 21^a by the time the cam shaft has made one complete revolution. The cam shaft carries a grooved cam 22. A lever 40, which is pivoted on the same stud 28, as that on which the gear segment 27 is pivoted, carries a roller 40^c which engages in the groove of the cam 22. This lever 40 comprises two parallel side members 40^a and a cross bar 40^b which extends between them and passes beneath the gear segment 27. As this lever 40 is swung upward by the cam 22 this cross bar, by engaging the gear segment, will swing it upward. There is fixed to the gear segment and projecting downward from the supporting axis thereof an arm 27^a, between which and a spring seat 41, carried by the left end of the lever 40, a stiff spring 42 is compressed. This spring is normally unyielding. Wherefore when the lever 40 is swung downward, it will push through this spring against the depending arm 27^a and will therefore rock the gear segment, causing it to move downward. Although this spring 42 is normally unyielding, as stated, it will yield in case the line transfer slide 15 meets with any unusual resistance, as, for example, if the line gets stuck.

There is a rock shaft 34 mounted on the framework of the machine having two arms 34^a, 34^b, one of which, projects into a notch in the pin 26, while the other is extended to a position where it will be engaged by a stud 10^a carried by the first elevator, whereby, when the first elevator has reached the top of its path, this rock shaft will have been rocked and the pin 26 will have been withdrawn from the cam groove 25^c in the sleeve 25. This, as before stated, will result, through the described mechanism, in causing the cam shaft to be connected with the rotating sleeve 21, whereby said cam shaft will begin to rotate. Before one complete revolution has been finished, the first elevator should be moved down, and thereby the pin 26 will be allowed to reenter the cam groove in the clutch sleeve 25, and this, as before stated, will result in unclutching the cam shaft from sleeve 21 when the cam shaft has completed one revolution. During this single revolution of the cam shaft, the line transfer slide 15 will have been moved to the right to the end of its path, and then back again to its starting position. The cam 22 which controls the movement of the gear segment 27 and therefore of the line transfer slide, is so shaped that when the transfer slide has reached the right end of its path, it will there be held for an appreciable time, during which the second elevator will have started up, and the first elevator should go down so that it will not interfere with the leftward movement of the said slide 15.

The mechanism for moving the second elevator 14 up and down may have any suitable construction. It may, for example, be like the elevator moving mechanism which is fully shown and described in Letters Patent No. 1,080,569. Therefore it has not been thought necessary to show in the attached drawing any more than the upper sprocket wheel 35 which is to be turned backward and forward at the proper times by said old mechanism, the sprocket chain 36 to which the second elevator is attached, the lower sprocket wheel 37 which is turned by said sprocket chain, and the pin 38 which controls the action of the clutch sleeve 39 which is also indicated by dotted lines in Fig. 1. Associated with this pin, however, is certain specifically novel mechanism by which the pin is moved at the proper time in the direction required to allow the clutch sleeve to act and in the direction for drawing the said clutch sleeve out of action.

The cam shaft 23 which, during each revolution, causes the back and forth movement of the line transfer slide 15, carries a disk 43 to which a tappet pin 44 is fixed. A rock shaft 46, which, for convenience, is tubular and is rotatably mounted on the rock shaft 34, has two arms 47 and 48. One of these has an inclined surface which projects into the path of said tappet pin so that when the cam shaft has reached the proper part of its single revolution, this lever will be lifted as the tappet pin engages and passes it. This will, of course, rock the rock shaft 46, whereby the other arm 48, which, at its end, is pivoted to the lower end of the vertically movable rod 49, will pull said rod down. The upper end of this rod is connected with a lever 50 which carries the pin 38, which, as before stated, controls the clutch sleeve 39. The downward movement of the rod 49 therefore withdraws this pin from disengagement with the clutch sleeve, whereupon the shaft 51 will make one complete revolution, during which the second elevator will move to its uppermost

position, and will there be held long enough for the matrices which it carries to be removed from it and transferred to the distributing rail, and will move down to its lowest position.

5 The mechanism for moving the space band transfer slide 16 consists of a train of reducing gears, of which the driving gear 53 is fixed to shaft 54 to which the sprocket 10 wheel 37 is fixed, and the terminal gear 55 engages rack teeth on the lower edge of said slide 16. This slide will therefore move to the right as the second elevator goes up and to the left as the second elevator 15 goes down. It is so moved by the same mechanism which moves the second elevator.

Having described my invention, I claim:

20 1. In a circulating matrix typographic machine, the combination of transfer rails, a space band magazine with which said rails communicate, a vertically movable first elevator, a vertically movable second elevator, a line transfer slide, and a space band transfer slide, with mechanism adapted to be set in operation by the first elevator for moving the line transfer slide, and mechanism adapted to be set in operation by said line transfer slide operating mechanism, for simultaneously moving the second elevator 25 and the space band transfer slide.

30 2. In a circulating matrix typographic machine, the combination of transfer rails, a space band magazine which is in communication with the transfer rails, a vertically movable second elevator, a space band transfer slide movable in a path parallel with said transfer rails and having an arm for engagement with the space bands which lie 35 between and are suspended from the transfer rails, means for raising and lowering said second elevator, and mechanism operatively connected with the elevator moving mechanism for simultaneously moving said 40 space band transfer slide.

45 3. In a circulating matrix typographic machine, the combination of transfer rails, a space band magazine which is in communication with the transfer rails, a vertically movable second elevator, a space band transfer slide movable in a path parallel with said transfer rails and having an arm for engagement with the space bands which lie 50 between and are suspended from the transfer rails, an upper driving sprocket wheel, a lower driven sprocket wheel, a chain belt running over said sprocket wheels and connected with said elevator, and mechanism 55 driven by the lower sprocket for moving 60 the space band transfer slide.

65 4. In a circulating matrix typographic machine, the combination of transfer rails, a space band magazine which is in communication with the transfer rails, a vertically 70 movable second elevator, a space band transfer slide movable in a path parallel with said transfer rails and having an arm for engagement with the space bands which lie 75 between and are suspended from the transfer rails, mechanism for raising and lowering said second elevator, mechanism intermediate of said space band transfer slide and the elevator moving mechanism compelling the slide to move synchronously with the elevator toward the space band magazine 80 when the elevator goes up and in the reverse direction when the elevator goes down.

5. In a circulating matrix typographic machine, the combination of transfer rails, a space band magazine which is in communication with the transfer rails, a vertically movable second elevator, a space band transfer slide movable in a path parallel with said transfer rails and having an arm for engagement with the space bands which lie 85 between and are suspended from the transfer rails, an upper driving sprocket wheel, a lower driven sprocket wheel, a chain belt which runs over said sprocket wheels and is connected with said elevator, a train of gears driven by said lower sprocket wheel, said space band transfer slide having a rack which is engaged by the terminal gear of said train of gears.

90 6. In a circulating matrix typographic machine, the combination of transfer rails, a space band magazine with which said rails communicate, a vertically movable first elevator, a vertically movable second elevator, a line transfer slide, and a space band transfer slide, mechanism adapted to be set in operation by the upward movement of the first elevator, for moving the line transfer slide, and mechanism adapted to be set in 95 operation by a part of the line transfer slide operating mechanism for moving the second elevator up and down and for simultaneously moving the space-band transfer slide back and forth.

7. In a circulating matrix typographic machine, the combination of transfer rails, a space band magazine with which said rails communicate, a first elevator having two depending parallel rails which are grooved to adapt them to support a line of matrices 115 and space bands, which elevator is capable of moving up to a position in which grooves in its rails are alined with the transfer rails, a second elevator having two depending grooved matrix supported rails, which elevator is adapted to occupy a position above the transfer rails, with its grooves alined with grooves in the first elevator, two transfer slides, viz. a line transfer slide having an upwardly extended arm adapted to engage the line in the first elevator and to push it out of the same onto said transfer rails and into the embrace of the second elevator, and a space band transfer slide adapted to push the space bands resting on 120 125 130

the transfer rails along the same and into the space band magazine, and mechanism for moving the line transfer slide in the functioning direction and then back to the starting position, and mechanism which begins to operate when the line transfer slide has completed its functioning movement for simultaneously moving the second elevator up and the space band transfer slide toward the space band magazine.

8. In a circulating matrix typographic machine, the combination of two parallel transfer rails, a space band magazine with which said rails communicate, a first elevator having two depending parallel rails, the opposed faces of each are formed with two pairs of parallel grooves, which elevator is capable of moving up to a position in which the lower grooves in its rails are alined with the transfer rails, a second elevator having two depending grooved matrix supporting rails, which elevator is adapted to occupy a position in which its rails are above the transfer rails and the grooves in its rails are alined with the upper grooves of the rails of the first elevator, two transfer slides movable in parallel paths, viz. a line transfer slide having a line engaging arm, which slide is adapted to push a line out of the first elevator to a position such that the matrices enter the embrace of the second elevator and the space bands become supported by

the transfer rails, and a space band transfer slide having an operating arm adapted to engage the space bands which are supported by the transfer rails and push them along said rails to the space band magazine, and mechanism for moving the line transfer slide, the second elevator, and the space band transfer slide.

9. In a circulating matrix typographic machine, the combination of transfer rails, a space band magazine with which they communicate, and a vertically movable second elevator having two depending grooved rails which, when the elevator is down, lie above said transfer rails, a space band transfer slide having an arm pivoted thereto, a spring for swinging said arm forward into operative position, an abutment adapted to engage said arm and thereby push it into the inoperative position, mechanism for moving the second elevator up and down, and mechanism which derives its power from and which moves concurrently with a part of the elevator moving mechanism for moving the said space band transfer slide.

In testimony whereof, I hereunto affix my signature in the presence of two witnesses.

DAVID PETRI-PALMEDO.
